I. G. SCOTT

TABLE LAMP

Filed March 16, 1928

INVENTOR

Irving G. Scott

UNITED STATES PATENT OFFICE.

IRVING G. SCOTT, OF NEW YORK, N. Y.

DESIGN FOR A TABLE LAMP.

Application filed March 16, 1928. Serial No. 25,885. Term of patent 3½ years.

To all whom it may concern:

Be it known that I, IRVING G. SCOTT, a citizen of the United States, residing at 181 Claremont Avenue, city of New York, in the county of New York and State of New York, have invented a new, original, and ornamental Design for Table Lamps, of which the following is a specification, reference being had to the accompanying drawing, forming part thereof.

The figure is a perspective view of a table lamp, showing my new design.

I claim;

The ornamental design for a table lamp as shown.

IRVING G. SCOTT.
